CLAIM

The ornamental design for a control panel, as shown and described.

DESCRIPTION

FIG. 1 is a front view of a control panel showing our new design;

FIG. 2 is a bottom view thereof;

FIG. 3 is a top view thereof;

FIG. 4 is a right view thereof;

FIG. 5 is a left view thereof; and,

FIG. 6 is a rear view thereof.

The broken lines shown in the drawings depict portions of the control panel that form no part of the claimed design. Color and texture may form part of the claimed design or may be replaced with uncolored and untextured material, without departing from the design disclosed.

In Figures where multiple icons are shown, the number of icons is not limited to what is shown and may be greater or less than what is shown.
